Attorney

UNITED STATES PATENT OFFICE.

HENRY H. TAYLOR, OF KEOKUK, IOWA.

REVERSIBLE GLOVE.

1,272,571.

Specification of Letters Patent. Patented July 16, 1918.

Application filed August 26, 1916. Serial No. 117,100.

To all whom it may concern:

Be it known that I, HENRY H. TAYLOR, a citizen of the United States, residing at Keokuk, in the county of Lee and State of Iowa, have invented certain new and useful Improvements in Reversible Gloves, of which the following is a specification, reference being had to the accompanying drawings.

This invention relates to gloves and particularly to the formation of gloves of canvas or other relatively soft flexible material, such gloves being used by brick layers, plasterers, and other workmen.

The general object of my invention is to provide a glove of this character which may be used either on the right hand or left hand of the wearer so that when the palm of the glove is worn through, the glove may be reversed and disposed on the other hand with the back of the glove used as a palm.

A further object is to provide a glove composed, except as regards the thumb, of two pieces or blanks and of such form that the blanks may be stitched to form the glove by ordinary plain sewing.

A further object is to provide a glove of this character having a thumb, the ordinary back of the thumb piece being provided with a reinforcement so that when the glove is reversed, the reinforcement will come over the inner face of the end of the thumb, thus adding to the wear of the glove.

Other objects will appear in the course of the following description.

My invention is illustrated in the accompanying drawings, wherein:

Figure 1 is a face view of the main blank from which my improved glove is made;

Fig. 2 is a face view of the blank for the fourth and third fingers and a portion of the back of the glove;

Fig. 3 is an inside face view of the blank 18;

Fig. 4 is an elevation of the glove looking toward the back; and

Fig. 5 is a face view of a thumb blank for a mitten.

In the drawings 10 designates the blank from which the glove is made. This blank has, in a general sense, the usual or ordinary shape of glove blanks and is slitted inwardly from the upper edge thereof whereby to provide the palm or face portions of the fingers 11, 12, 13 and 14 and the backs 14^a and 13^a which fit the face portions 14 and 13 respectively. The portions 14 and 14^a are not di-

vided from each other by a slit but the blank is intended to be folded on the line a—a so as to bring the portion 13^a over the portion 13 and the portion 14^a over the portion 14. 60 One side edge of the blank beneath the portion 13^a is cut away as at 15 and the lower edge of the blank at a point beneath the line a—a is cut out so as to form the half fourchette 16 which forms the inner face or palm 65 member of the thumb of the glove.

Coacting with the blank is a blank 17 formed to provide the portions 11^a and 12^a, divided from each other by a median slit and intended to form the backs of the fingers 11 and 12. This blank 17 is also cut away as at 15^a. A separate thumb piece 18 is formed, having the shape illustrated in Fig. 3, which forms the outer portion of the thumb in the completed glove and coacts 75 with the half fourchette 16. Disposed upon the inner face of this piece 18 adjacent the tip thereof is a reinforcement or partition 19 which is stitched around its top and side edges as at 20. The lower portion of the reinforce or partition 19 is narrower than the adjacent portion of the thumb blank 18 to afford portions b adapted to be secured to the side edges of the thumb palm member 16. In use, the thumb is adapted to be disposed 80 between the face of the glove thumb and the partition whenever desired and whether the glove be worn as a right or a left hand glove.

In completing the glove from the blank 90 thus formed, the portion 17 is attached to the blank 10 by stitching 21. The blank 10 is then folded upon the dotted lines a—a and the edges 15 and 15^a are stitched together, thereby forming a longitudinal seam 95 on the back of the glove, when the glove is first worn, and on the palm of the glove when the glove has been reversed. The free edges of the finger portions are stitched together in the usual manner, after which the 100 thumb piece 18 is stitched to the member 16 and to the body of the glove. It will be understood, of course, that the finger portions 11, 12, 13 and 14 and 11^a, 12^a, 13^a, and 14^a are large enough so that no separate 105 fourchettes are necessary, thus greatly cheaping the construction of the glove.

After the glove is completed as above set forth, the wrist is added which may be knitted or otherwise formed as desired. It 110 will be seen that a glove constructed as above described is very cheap and simple

and that a very economical use may be made of the material from which the blanks are cut out. The thumb blank shown in Fig. 3 5 may also be used for mittens and the reinforcement will, of course, operate or be used in the same manner as for gloves.

In Fig. 5 I show the thumb piece 18^a of a mitten (I have not shown a mitten, as its construction is well understood) provided 10 with a reinforcing element 19^a. This thumb piece blank 18^a is of such shape that the two portions or wings *c* and *d* may be turned over upon each other and stitched together to form the complete thumb of the glove.

One of the main objects of my invention 15 is to so form the blanks for the glove that economy of time may be secured in stitching the blanks together. It will be noted that my blanks require initially that only one 20 seam be stitched up the back of the body of the glove. In other words, the seam extends only up the back of the glove from the wrist to the junction of the fingers 12^a and 13^a, and there is no seam on the palm of the 25 hand. Thus instead of stitching up the other side or palm of the glove, the threads, after the seam up the back is made, are broken and the body is passed to the workman who does the closing of the fingers, it being, of 30 course, understood that the blank 17 has been stitched to the body 10 initially. Further it will be noted that in my glove there are no seams on the palm of the glove until 35 the glove is reversed and that there are no seams across the bases of the fingers. With my invention, furthermore, only two operations are necessary to complete the thumb, namely, one operation to cover the stitching of the blank 19 to the thumb piece 18 and 40 a second operation to stitch the thumb on the glove.

In making up my blank, one operation covers the stitching of the blank 17 onto the body of the glove. The portions 14^a and 13^a 45 are then folded over 14 and 13 and stitched to the margin of the part 17. Then the fingers are stitched and then the thumb blank is stitched.

I provide for a great saving of time and 50 labor in the cutting out of gloves according to my invention, as the fingers are all cut with the same operation as the body of the glove and furthermore, there is a saving of time in stitching up as only plain sewing is 55 necessary.

Having described my invention, what I claim is:

1. A reversible glove formed from a plurality of blanks, one of the blanks being cut 60 to provide the face of the thumb of the glove and the faces for the little finger, third finger and second finger, the back and front of the first finger and the back of the second finger, the faces for the little finger and the 65 third and second fingers being separated

from each other and from the back and front of the first finger, and the back of the second finger being separated from the back and front of the first finger, the back and front of the first finger being connected to each other, said blank also forming part of the back of the glove and at its margin opposite the fingers being cut to form the palm member of the thumb, the other blank being 70 stitched to the first named blank at its margins and formed to provide the remainder of the back of the glove and the backs of the little finger and the third finger, and a separate thumb piece attached to the palm member of the thumb and to the body of the 80 glove.

2. A reversible glove formed from a plurality of blanks, one of the blanks being cut to provide the faces for the little finger, third finger, and second finger, the back and front of the first finger and the back of the second finger, the faces for the little finger and the third and second fingers being separated from each other and from the back and front of the first finger, and the back of the 85 second finger being separated from the back and front of the first finger, the back and front of the first finger being connected to each other, said blank also forming part of the back of the glove and at its margin opposite the fingers being cut to form the palm member of the thumb, the other blank being stitched to the first named blank at its margin and formed to provide the remainder of the back of the glove and the backs of the little finger and the third finger, a separate thumb piece attached to the palm member of the thumb and to the body of the glove, and a partition secured around its side and top 90 margins to the inner face of the separate 95 thumb piece.

3. A reversible glove formed from a plurality of blanks, one of the blanks being cut to provide the faces for the little finger, third finger and second finger, the back and front of the first finger and the back of the second finger, the faces for the little finger and the third and second fingers being separated from each other and from the back and front of the first finger, and the back of the second finger being separated from the back and front of the first finger, the back and front of the first finger being connected to each other, said blank also forming part of the back of the glove and at its margin opposite the fingers being cut to form the palm member of the thumb, the other blank being stitched to the first named blank at its margin and formed to provide the remainder of the back of the glove and the backs of the little finger and the third finger, a separate thumb piece attached to the palm member of the thumb and to the body of the glove, and a partition secured around its side and top 100 margins to the inner face of the separate 105 thumb piece.

face of the separate thumb piece, the lower portion of said partition being narrower than the adjacent portion of the separate thumb piece to permit said adjacent portions 5 of the thumb piece to be attached to the thumb palm member independently of the partition.

4. A reversible glove formed from a plurality of blanks, one of said blanks being 10 cut out to provide the front for the little finger, third finger and second finger, the back and front of the first finger and the back of the second finger, the fronts for the little finger and the third and second fingers 15 being separated from each other and from the back and front of the first finger, and

the back of the second finger being separated from the back and front of the first finger, the back and front of the first finger being connected to each other, said blank also 20 forming part of the back of the glove, a second blank being stitched to the first named blank at its margins and formed to provide the remainder of the back of the glove and the backs of the little finger and the third 25 finger.

In testimony whereof I hereunto affix my signature in the presence of two witnesses.

HENRY H. TAYLOR.
